United States Patent Office.

LUMAN ROGERS, OF PITTSBURG, PENNSYLVANIA.

Letters Patent No. 98,887, dated January 18, 1870.

IMPROVEMENT IN HORSE HAY-FORKS.

The Schedule referred to in these Letters Patent and making part of the same.

To all whom it may concern:

Be it known that I, LUMAN ROGERS, of the city of Pittsburgh, in the county of Allegheny, and State of Pennsylvania, have invented a new and useful Improvement in Hay-Forks or Elevators; and I do hereby declare the following to be a full, clear, and exact description thereof, reference being had to the accompanying drawings, making a part of this specification, in which—

Figure 1 is a side elevation of my improvement, a portion of the handle of the fork being cut away, the better to illustrate it;

Figure 2 is a sectional view through α α , fig. 1; and

Figure 3 is an enlarged perspective view of the sliding bolt by which the locking is effected.

Like letters of reference indicate like parts in each.

My invention relates to the construction of that class of harpoon hay-forks or elevators, in which the prongs or barbs are locked in a distended position, by means of a pair of jaws, which are so constructed as to embrace, clamp on to, or bear against some fixed part of the main stock, stem, or sheath; and

The nature of it consists in the construction of an improved device for locking and unlocking such jaws.

To enable others skilled in the art to make and use my invention, I will proceed to describe its construction and mode of operation.

The main stock, a and centre-rod b , prolonged to the usual length, carry a point or penetrator, and barbs or prongs, all of the usual or any known construction.

Connected with the upper end of the stem b , is a pair of jaws d d' , at least one of which is movable.

The other may be hinged to the stem b , or be an extension of it, as shown in the drawing. The lower end of the fixed jaw d is grooved or boxed deep enough for the lower end of the movable jaw d' to be hinged therein by a hinge-pin, e , and also so as to admit the required motion, though other suitable mode of hinging may be substituted.

Below the point of hinging, a spring, e' , of spiral or other suitable form, is inserted between the jaws d d' .

Recesses or eyes s s' are made in the inner face of the jaws d d' , each large enough to clamp securely on to the main pin e of the stock a .

To the fixed jaw d is attached a handle, h , of ring-like or other suitable shape.

The upper end of the movable jaw d' plays through a slot, h' , in its base, which slot is long enough to admit of the forward and backward movement of the jaw d' .

On the upper end of the jaw d' , and inside the handle h , is hinged a tripper, g , which has a stop, g' , on its forward side, and a shoulder, g'' , on the rear, against which operates the upper end of a flanged bolt, m , which plays in a mortise, i , made in the upper end of the movable jaw d' .

On either or both sides of the bolt m , and about midway between its ends, is a flange or flanges, n , each of which acts as a feather to lock the jaw d' .

To this end, the slot h' is made, at the locking-point, of T-shape, as at i , the T-part being of sufficient size to admit the flanges n .

Also, a socket, o , is made in the bottom of the mortise i , for the lower end m' of the bolt m to work in, and a spiral spring, o' , keeps the bolt m well up against the shoulder g'' .

The devices described are so arranged and put together, that when the tripper g is forward, with its stop g' resting on the base of the handle h , the flanges n will enter the T-part i of the slot h' , and at the same time the body of the bolt m , still remaining between the walls of the mortise i , the jaws d cannot recede from the locking-position shown, whereby it is made to lock on to the rivet e , which fills the eyes s .

In order to distend the barbs or prongs, the tripper g is thrown back by the use of the cord p , whereby the flanges n of the bolt m are thrown out of and below their position in the T-slots i , when their hold on the handle h is released.

The continued pulling of the cord p , pulls the jaw d backward, the upper end of the bolt m sliding in the groove h' , and then the stem b and jaws d d' are forced down through the stock a , till the rivet e enters the eye s . The jaw d then comes back to its former position, and locks the barbs in a distended position, the flanges n entering the T-slot i in the handle h , as before.

The load of hay being hoisted to the desired position, the jaw d is thrown back, as before, when the devices come again to the position shown in the drawing, and the load is discharged.

I do not limit myself, in my invention, to the precise form shown, of bolt m with flanges or feathers n , but include any form of device in which a movable bolt, key, flange, or feather, connected with the upper end of the movable jaw d' , shall, while being firmly secured in its own seat, interlock into the handle h , or vice versa, substantially in the manner described.

What I claim as my invention, and desire to secure by Letters Patent, is—

1. The combination, with a handle, h , and movable jaw, d' , of a pair of jaws of a harpoon hay-fork, a movable bolt, key, flange, or feather, connected with one, and interlocking with the other, substantially as described.

2. A tripper, g , in combination with a feathered or flanged locking-bolt m , the latter operating through a slot in the handle h , and into a recess or mortise in the jaws d' , substantially as described.

In testimony whereof, I, the said LUMAN ROGERS, have hereunto set my hand.

LUMAN ROGERS.
